[57] CLAIM

The ornamental design for an attache lock latch assembly, substantially as shown and described.

DESCRIPTION

FIG. 1 is a perspective view of an attache lock latch assembly showing our new design;

FIG. 2 is an enlarged top plan view thereof;

FIG. 3 is an enlarged perspective view thereof;

FIG. 4 is an enlarged perspective view of a second embodiment thereof;

FIG. 5 is an enlarged perspective view of a third embodiment thereof;

FIG. 6 is an enlarged perspective view of a fourth embodiment thereof, and

FIG. 7 is an enlarged sectional perspective view of the embodiment of FIG. 6.

The broken-line showings of the attached case and portions thereof are for illustrative purposes only and form no part of the claimed design.
